UNITED STATES PATENT OFFICE.

SAMUEL G. GOSS, OF CHICAGO, ILLINOIS, ASSIGNOR TO THE GOSS PRINTING PRESS COMPANY, OF CHICAGO, ILLINOIS, A CORPORATION OF ILLINOIS.

STEREOTYPE-CASTING BOX.

933,172.

Specification of Letters Patent. Patented Sept. 7, 1909.

Application filed December 11, 1908. Serial No. 467,068.

To all whom it may concern:

Be it known that I, SAMUEL G. Goss, a citizen of the United States, residing at Chicago, in the county of Cook and State of Illinois, have invented certain new and useful Improvements in Stereotype-Casting Boxes, of which the following is a specification, reference being had to the accompanying drawings.

10 My invention relates to casting-boxes for casting stereotype plates for printing presses, and has for its object to provide certain new and useful improvements in the construction and operation of such boxes, as 15 will be hereinafter fully set forth.

In the accompanying drawings,—Figure 1 is a side elevation illustrating my improved casting box in position to receive the matrix; Fig. 2 is an enlarged detail, being a sectional view of a portion of the core showing the grooves therein; Fig. 3 is an under side view of a case, some parts being broken away; Fig. 4 is a longitudinal vertical section of a casting-box with the core in operative position after a cast has been made; Fig. 5 is a plan view of the inner surface of the upper portion of the case; Fig. 6 is a cross-section on line 6—6 of Fig. 5; Fig. 7 is a plan view of the body of the core, showing one arrangement of the grooves cut in the surface thereof; Fig. 8 is a similar view, showing a modified arrangement of the grooves; and Fig. 9 is a cross-section of the casting-box taken on line 9—9 of Fig. 3.

35 Referring to the drawings,—10 indicates the bed-plate of the machine, 11 the core of the casting-box and 12 the case thereof. As shown in Fig. 1, the core is mounted in a vertical position on the base-plate 10 and 40 remains in such position, being secured to the base-plate in any suitable way, as, for example, by bolts 13. The case 12 is so mounted as to be movable into either a horizontal position, as shown in Fig. 1, or to a 45 vertical position, as shown in Fig. 4,—it being in the latter position fitted to the core so as to be in position to receive a cast. In the construction shown the case is provided with brackets 14 on its under side having teeth 50 15 which mesh with the teeth of a curved rack 16 secured on the base-plate so that as the case is rocked to the left, as shown in Fig. 1, it moves over toward and fits upon the core. At that end which is lowermost 55 when it is in operative position the case is

provided with standards 17 having at their lower ends sockets 18 which fit on trunnions 19 and serve to support the case when in operative position. The core and case are of the usual semicylindrical form, and, as best 60 shown in Figs. 3 and 9, the case is provided with a water-chamber 20 by which it is water cooled. The water-chamber is provided with longitudinally-extending partitions 21—22—23, the partitions 21—23 extending from the upper end, as shown in Fig. 3, down to near the lower end of the case, while the partition 22 extends from the lower end thereof to a point near the upper end of the water-chamber. Thus four compartments are provided and the water is compelled to flow four times the length of the water-chamber between the point of its admission thereto and the point of its exit therefrom. The several water passages are 70 indicated by numbers 24, 25, 26 and 27, respectively, in Fig. 9.

28 indicates a pipe connection communicating with the chamber 24, and 29 indicates a similar connection communicating with 80 the chamber 27.

30—31 indicate hose pipes connected, respectively, with the connections 28—29. Water is admitted through one of these pipes and is discharged through the other. Any 85 suitable means may be provided for maintaining a circulation of the water during the operation of casting. Thus the temperature of the casing is kept approximately uniform.

As best shown in Figs. 5 and 6, the case 90 12 is provided near its upper end—i. e. the end which is uppermost when the case is in operative position—with a series of longitudinally-extending channels or grooves 32 which extend in the inner surface of the 95 casing from its upper end down to the upper edge of the matrix 33, as shown in Fig. 4. Such channels serve to permit the escape of air while a cast is made, providing passages between the upper portion of the case and 100 the usual sheet-iron plate 34 which is fitted into the upper end of the case before the metal is poured thereinto.

The core 11 is provided upon its operative surface with a series of grooves or channels 35 which extend diagonally in the manner shown in Figs. 7 and 8—that is to say, the grooves or channels 35 trend angularly with reference to both the longitudinal or the transverse axis of the core. The purpose 110

of providing the grooves and arranging them in the manner stated is to form correspondingly disposed ribs on the inner surface of the stereotype plate instead of the usual transverse ribs which have heretofore been provided. The advantage of arranging the ribs angularly or diagonally is that the strains to which the plates are subjected in cooling are equalized and more generally distributed so that the plate is not so apt to be damaged, and moreover better results are secured in the matter of shaving the ribs in finishing the plate. A further important advantage is that by so disposing the ribs upon the plate a practically continuous support is provided for the plate as the successive ribs overlap and coöperate to provide a complete support for the printing surface. The specific arrangement of the grooves or channels in the core may, of course, be varied to a considerable extent without departing from my invention.

36 indicates a latch which is pivoted upon a standard 37 and is adapted to engage a hook 38 carried by the case, as shown in Fig. 1. Said latch is connected by a connecting-rod 39 with a foot-lever 40 and is held normally in its uppermost position by a spring 41. The arrangement is such that by depressing the lever 40 the latch may be disengaged from the hook, thereby releasing the case and permitting it to be turned to operative position.

In operation the matrix is placed in the case when the latter is in its horizontal position, as shown in Fig. 1. The case is then turned to a vertical position, as shown in Fig. 4, and the molten metal poured in. The longitudinal channels 32, which are then

in an upright position, afford ready means 40 for the escape of air, thus preventing the retention of bubbles in the plate. After the plate has been cast it is removed and finished in the usual way, the diagonal ribs facilitating the operation of shaving as well as 45 strengthening the plate, as hereinbefore described.

That which I claim as my invention and desire to secure by Letters Patent is,—

1. In a stereotype casting-box, the combination of a core and a case provided with a circuitous water passage, and inlet and outlet pipes communicating with the ends of said passage.

2. A stereotype casting-box, comprising a core and a case having one or more passages for the escape of air.

3. A stereotype casting-box, comprising a core and a case having one or more longitudinally-disposed passages in its upper end 60 for the escape of air.

4. A core for casting-boxes having a series of inclined grooves for forming inclined ribs in the plate.

5. A core for casting-boxes having a series 65 of overlapping inclined grooves for forming inclined ribs in the plate.

6. A core for casting-boxes having a series of grooves extending at an angle to the longitudinal and transverse axes of the core. 70

7. In a stereotype casting-box, the combination of a core and a case, said core having means for forming inclined ribs in the plate.

SAMUEL G. GOSS.
